AUTOMOBILE STONE SHIELD

Edward O. Sheard, Detroit, Mich., assignor to
Chrysler Corporation, Highland Park, Mich., a
corporation of Delaware

Application August 13, 1949, Serial No. 4,457

Term of patent 7 years

(Cl. D14—6)

To all whom it may concern:

Be it known that I, Edward O. Sheard, a citizen of the United States, residing in the city of Detroit, county of Wayne, and State of Michigan, have invented a new, original, and ornamental Design for an Automobile Stone Shield, of which the following is a specification, reference being had to the accompanying drawing, forming part thereof, in which:

Fig. 1 is a broken line representation of an automobile fender, showing my novel design for an automobile stone shield, the dotted outline of an automobile fender being for illustrative purposes only;

Fig. 2 is a side elevation of the stone shield;

Fig. 3 is a top plan view thereof taken in the direction of the arrow 3 in Fig. 5;

Fig. 4 is a front elevation of the stone shield;

Fig. 5 is a vertical section taken on the line 5—5 of Fig. 2; and

Figs. 6 and 7 are horizontal sections taken on the lines 6—6 and 7—7 respectively of Fig. 2.

I claim:

The ornamental design for an automobile stone shield, substantially as shown and described.

EDWARD O. SHEARD.
